UNITED STATES PATENT OFFICE.

WILLIAM W. TREVOR, OF LOCKPORT, AND DELEERT A. BEREAN, OF BARKER, NEW YORK, ASSIGNORS TO TREVOR MANUFACTURING COMPANY, OF LOCKPORT, NEW YORK.

MACHINE FOR OPERATING ON BARRELS AND THE LIKE.

Application filed March 26, 1924. Serial No. 702,141.

This invention relates to improvements in hoop driving and barrel leveling machines, and more particularly to machines used for driving the usual temporary heavy trussing 5 hoops on trussed barrels or other containers and for leveling the ends of the staves thereof or truing up the container bodies preparatory to finishing the ends of the staves and applying the permanent hoops. 10 The invention is particularly applicable to machines of this sort adapted to the manufacture of barrels known as "slack" barrels but the same may also be used in connection with other forms of barrels, containers or 15 packages.

In the manufacture of a barrel or like package it is customary to assemble the required number of staves by arranging them in a setting up form, where they are drawn 20 together by suitable means, and temporary truss hoops are placed over the ends of the staves to hold them in barrel formation. These truss hoops are relatively thick metal rings and they are placed over the staves 25 near the opposite ends, after which they must be driven tightly on the staves sufficiently far to hold them securely during the subsequent operations on the barrel.

The invention relates to machines for 30 driving the temporary hoops on the staves and leveling the staves as stated.

Machines of this character have been provided having oppositely disposed driving heads, one or both of which reciprocate toward the barrel being operated upon. The driving heads include a plurality of driving and guiding members, arranged to engage the hoops on the barrel. Leveling heads and centering cones or devices are also provided 35 which are usually arranged on the driving heads whereby the ends of the staves are leveled and centered. It has been customary in these machines for the driving heads and the leveling and centering heads to be 40 rigidly secured relatively to each other and to be moved a definite distance to engage the ends of the barrel and drive the hoops thereon, the drivers being resiliently arranged so as to yield or be restrained when engaging 45 the hoops. In the use of such machines, should the staves of the barrel exceed the usual length, the rigidly arranged leveling and centering heads will engage their opposite ends and by reason of the fact that these

heads must move to definite points according 55 to the throw of the actuating means, they will compress the excessively long staves to a harmful degree with resultant breakage and loss of material and time. The action of the hoop drivers is not uniform and the hoops 60 are not necessarily driven to the same distance apart but the distance between the hoops may vary on different barrels of same size. In machines of this sort it has been 65 customary to provide different sizes of leveling heads, centering cones, or both, to permit the machines to operate on barrels or packages of different sizes. Up to the present time, machines for the purpose stated, have 70 been relatively expensive to produce, necessitating the use of accurately machined parts, of heavy construction, such that it has been impractical to adopt such machines for use in localities where only a limited demand for barrels exists. For instance, in certain fruit 75 growing districts where barrels are required during only a short period of each year, it would not pay the individual users or small cooperage concerns to purchase such expensive machines, as a relatively large investment would remain idle and unproductive 80 during a greater portion of each year.

One of the objects of the present invention is to provide a hoop driving or trussing machine of relatively simple and inexpensive 85 construction and of light weight, such that it may be advantageously introduced in communities where only an intermittent demand therefor exists and so that it may be easily 90 transported from place to place if desired.

Other objects are to provide a machine of this character with improved stave leveling and barrel centering means; also to provide a combined leveling head and centering form or cone of a single metal part of relatively 95 simple form; also to so construct and arrange the opposed leveling and centering means that these parts will automatically 100 adjust themselves to compensate for variations in the length of the staves, when set for a given size of barrel, without breaking or injuring the staves; also to provide improved driving and guiding devices for forcing the hoops on the barrels so constructed and arranged that in the operation of the 105 machine, the hoops will be positively driven towards each other from opposite ends of the barrel to definite relative positions, regard-

less of variations in the length of the barrel staves; also to provide the driving devices with improved guide means adapted to facilitate the quick and accurate positioning 5 of the barrels on the machine without requiring special care on the part of the operator, and to provide the driving devices with improved means whereby they may automatically adjust themselves to variations or inequalities in the hoops or barrels: also to provide means in the form of auxiliary rings and attaching devices therefor whereby the machine may be easily and quickly adapted to barrels and packages of different diameters, without necessitating the removal or changing of the leveling heads, by attaching an auxiliary ring of the required diameter directly over the centering cone.

Another object is to provide an improved 20 and simplified adjustable connection between the driving heads and the actuating means therefor, whereby the machine may be easily and quickly adjusted to change the stroke of the machine to adapt it to operate 25 on barrels or packages of different lengths. Still other objects of the invention are to improve, generally machines of this sort in the other respects hereinafter described and set forth in the claim.

30 In the accompanying drawings:

Fig. 1 is a front elevation of a truss hoop driving and stave leveling machine embodying my invention.

Fig. 2 is a longitudinal sectional plan view 35 thereof on line 2—2, Fig. 1.

Fig. 3 is a vertical sectional elevation thereof on line 3—3, Fig. 2, showing the driving heads and associated devices at the extreme limit of the driving stroke.

40 Fig. 4 is a fragmentary similar view of the machine at the moment of engagement of the hoop driving devices with the hoops at opposite ends of the barrel.

Fig. 5 is a sectional plan view of the 45 machine on an enlarged scale showing an auxiliary centering ring applied thereto.

Fig. 6 is a fragmentary vertical section thereof on an enlarged scale on line 6—6, Fig. 5 showing the securing means for an 50 auxiliary centering ring.

Figs. 7 and 8 are fragmentary enlarged 55 vertical sections on line 7—7 Fig. 5 showing two different adjustments of one of the driving devices.

Fig. 9 is a sectional plan view of one of the driving devices on line 9—9, Fig. 7.

Fig. 10 is a fragmentary vertical section 60 showing the positioning means for adjusting an auxiliary centering ring on the centering cone.

The machine shown in the drawings comprises generally a main frame including an upper horizontal frame member 10, on which the gears and driving means are mounted, 65 spaced parallel upright posts or tie rods 11

connected to the member 10 and adapted to form guides for a reciprocating driving head 12. The opposite ends of the rods 11 are connected to a combined base plate and stationary driving head 13. The member 10 and head 13 are further connected by a central rear upright 14 and intermediate tie rods 15.

The reciprocating driving head 12 is preferably of circular form and provided with 75 opposite lateral bearings or portions 16 slidably embracing the tie rods 11 for guiding the head in its movements toward and from the stationary driving head 13. The driving head 12 is preferably adapted to be continuously reciprocated so that the barrels or packages may be operated upon one after another, as quickly as they can be put into the machine and removed therefrom. Any 80 suitable means may be utilized for so actuating the driving head, such as a drive shaft 20 and spur pinion 21, meshing with the gear 22 on a counter shaft 23. The counter shaft is provided with a fixed crank arm 24 to the outer end of which one end of a pitman or connecting rod 25 is pivotally connected, the other end of the connecting rod 25 being pivotally connected at 26 to transverse reinforcing ribs or flanges 27 on the reciprocating driving head 12. The drive shaft may 85 be rotated by the pulley 28 or otherwise. Means are preferably provided for adjustably positioning the head 12 relative to the shaft 23 whereby it may be changed as required to approach nearer to or farther 90 from the fixed head 13 when at the extreme end of its stroke so that barrels or packages of various lengths may be effectively operated upon in the machine. For this purpose, the connecting rod 25 is provided with 95 shackle portions 30, 31 at its opposite ends which are connected by a turn buckle 32 having right and left hand threaded portions 100 at its ends screwing into the parts 30, 31. By these means the length of the connecting rod 25 may be varied by rotating the turnbuckle 32 in one direction or another. Any other suitable means may be used for 105 varying the length of the connecting rod 25. The driving head 13 may be of any suitable construction adapting it to form a base 110 or support for the machine and it is therefore provided with the rearwardly extended part 13^a to which the rear upright 14 and tie rods 15 are connected. Feet or lugs 35 depending from the edges of the head 13 115 form convenient means whereby the machine may be supported on a floor.

Each of the driving heads 12 and 13 is 120 provided with improved adjustable hoop driving and barrel guiding devices. As shown in the drawings, four of such devices 36 are arranged radially at equidistant 125 points on each head, and each device comprises a hoop engaging and driving finger 130

or part 37 pivoted on a radially adjustable bracket 38 and extending perpendicularly from the driving head toward the opposite head. Each bracket 38 is provided with elongated slots 39, and bolts 40 extend therethrough into the head whereby the brackets can be adjusted to different positions radially of the head. The driving devices 36 are preferably also provided with improved means for guiding the barrels into position when placed into the machine and for engaging and restraining the hoops against lateral displacement or distortion when being driven on the barrel. These means comprise hook members 41, secured to or formed on the driving fingers 37 and having curved parts 42 adjacent the hoop engaging portions of the fingers 37. The parts 42 are curved outwardly and backwards and extend radially relatively to the axes of the driving heads, see Figs. 3-5 and 7 and 8. Two of the driving devices 36, preferably the two rearmost devices of the lower driving head 13, are provided with modified guide fingers 42^a see Figs. 3 and 5. These fingers 42^a are longer than the other fingers 42 and extend upwardly and flare outwardly as shown. When a barrel or container is placed in the machine it is usually held by the upper end and is moved diagonally into the machine, lower end foremost, so that the rear portion of the lower edge, is higher than the front portion. The fingers 42^a are therefore adapted to engage the rear portion of the lower edge to guide the barrel downwardly into position and prevent the rear portion of the barrel from being improperly positioned over or outwardly beyond the rear driving devices.

Additional means for centering the barrel relatively to the axis of the machine are provided in connection with the novel leveling heads and centering cones associated with the driving heads 12 and 13. In the preferred construction shown in the drawings a leveling head and centering cone 45 is provided for each driving head. Each of these devices 45 comprises a one piece casting or part having an annular stave engaging and leveling flange 46 positioned adjacent the driving devices 36 and spaced from the driving head, and a central truncated cone or tapered part 47 extending from the flange 46 towards the opposite driving head, with its largest diameter in the plane of its connection with the flange 46 and having its center coincident with the axis of the driving heads. This largest diameter of the centering cone 47 is preferably substantially that of the internal diameter at the ends of the smallest barrel or container to be operated on. The flanges 46 are provided with radially disposed notches 48 through which the driving devices 36 extend, so that, in the normal position of the parts, the guide fingers 42, 42^a of the driving devices are substan-

tially in the position shown in Fig. 1. Thus when a barrel is inserted in the machine, as explained, the lower end of the barrel will be guided by the fingers 42, 42^a of the lower driving devices into engagement with the centering cone, and the barrel will then move downwardly on and be centered by the lower cone 47 with its axis coincident therewith and also with the driving head 12 and the other centering and leveling device 45 associated therewith.

The leveling and centering devices 45 are preferably guided and resiliently mounted on their respective driving heads so that when the upper driving head 12 moves downwardly towards a barrel on the machine and the drivers of the two driving heads engage and force the hoops towards each other farther on the barrel, the opposite ends of the barrel staves are simultaneously engaged by the flanges 46 for the purpose of leveling the staves and squaring up the barrel, the leveling and centering devices will be permitted to "give" or have a yielding engagement with the ends of the staves. By this means, breakage of staves is prevented in cases where the staves are over length while nevertheless the hoops will be driven to the desired positions. The preferred arrangement for this purpose is as follows:—

Each of the leveling and centering devices 45 is provided with a central boss or hub 50 having a stud 51 secured therein which extends outwardly and is adapted to slide in a central guide sleeve 52 in the adjacent driving head, whereby the leveling and centering device is centered and aligned with reference to its driving head. At equidistant points on the flange 46 are bolts or pins 53 extending loosely through holes in the flange 46 into and through registering holes in the adjacent driving head. Coil springs or the like 54 surround the bolts 53 between the leveling device and the driving head 110 which tend to separate these members, while nuts 55 on the outer ends of the bolts are adapted to engage the outer faces of the driving heads to restrain and limit the distance to which said members may be separated. The nuts may be tightened or loosened as required to vary the tension of the springs and the distance between the leveling device and its driving head.

In the use of the machine, a barrel having the truss hoops X on the ends as explained, is placed in the machine in the manner described during the time that the upper driving head is raised by the crank 24. The lower end of the barrel will surround the centering cone 47 of the lower leveling and centering device 45 with the ends of the staves resting on the flange 46, and the hoop X will be adjacent the ends of the driving fingers 37. As the upper driving head 12

descends, the upper ends of the barrel staves will be first engaged by the flange 46 of the upper leveling and centering device 45 and the continued downward movement of the 5 driving head 12 will cause the ends of the upper driving fingers 37 to engage the upper hoop. The hoops at the opposite ends of the barrel are now engaged by their respective driving fingers 37 and the further 10 downward movement of the upper driving head 12 will force these hoops towards each other on the barrel to a like distance for the reason that the ends of the upper and lower driving fingers are the same distance from 15 their respective driving heads. At the same time, owing to the engagement of the opposite ends of the staves with the upper and lower leveling and centering devices 45, these devices will be retarded, or held from 20 following the driving devices 36 to a substantially equal degree by the yielding of the coil springs 54. If, however, the ends of the staves at one end of the barrel project beyond the adjacent hoop to a greater extent than at the other end, the leveling device 45 at this end will yield and so prevent breaking or splitting of the staves, but the hoops will, on account of the fixed movement of the upper drivers, nevertheless be 25 driven to their required positions at a fixed predetermined distance apart.

Thus the hoops are driven on the barrels to predetermined points and the distance between them will always be the same irrespective of slight differences in the lengths of the staves; also the described resilient arrangement of the leveling and centering devices permits slight relative endwise movements of the staves, so that, should one or 30 more of the staves be inadvertently positioned so that one end projected some distance beyond the others it will be engaged by one or the other of the leveling devices and pushed into position between the adjacent staves by a sliding movement. The barrels are thus trued or leveled in a practical and efficient manner. The described arrangement whereby the hoops are definitely positioned relatively to each other 35 also enables these hoops to be used as gages for subsequently trimming the ends of the barrels, thereby insuring the production of barrels of uniform length.

The present invention includes the provision of improved means, whereby the machine is adapted to be used on different sizes of barrels or containers without the necessity of removing the driving heads or leveling and centering devices and substituting 40 others of different size. The preferred embodiment includes the provision of auxiliary centering rings of different outside diameters adapted to surround the centering cones and be secured thereto so as to increase the 45 diameter of the centering cones. A pair of

these rings of the same size are used, one on the upper, and one on the lower centering cone 47, for each larger size of barrel to be operated upon, and it should be understood that the driving and guide devices 36 are to be adjusted radially in the slots 48 in accordance with the size of centering ring used. As shown in Figs. 5, 6, 8 and 10, an auxiliary centering ring 57 having inner and outer inclined walls 58, 59 corresponding to 50 the slope, and preferably of the height of the centering cone is illustrated. The outer diameter of this ring is the same as the inside diameter of the end of the barrel with which it is to be used, and to insure the proper positioning of the ring on the cone, means of suitable sort are provided whereby the ring may be placed so that a definite point on the ring will always register with a selected point on the cone. For this purpose the ring 57 and the cone 47 are each provided with a registering hole as at 60, 60^a respectively and a dowel pin 61 is adapted to be inserted through both holes when they are brought into register, see Fig. 10. 55 The ring may now be secured to the leveling and centering device in any suitable way, as for instance by the use of screws 62, passing through apertures 63 in the ring and into threaded holes 64 in the flange 46 see Figs. 5 and 6. Any other suitable registering and securing means may be used for the purpose described.

It is desirable that the driving and guide fingers 37, 41 of the driving devices 36 be arranged so that, should the barrel or container bulge, or be contorted or deformed adjacent the hoops, the driving fingers may yield away from or ride over such inequalities, without cutting into or otherwise injuring the staves, or by catching on the staves, prevent the proper driving on of the hoops. The driving fingers 37 and guide fingers 41 are therefore arranged so as to yield radially outward when conditions as stated above are encountered. In the drawings the end of each driving finger adjacent the pivot pin 65 is provided with a stop shoulder 66 adapted to engage a fixed part, such as the driving head to limit its movement towards the axis of the machine, and a coil spring 67 is interposed between the fingers and a fixed lug 68 on the bracket 38. The coil spring acts to press the finger inwardly and yieldingly hold the finger 37 in its normal position, but will yield against pressures exerted from the opposite side of the driving finger 37 which pressures would be in planes parallel with the axis of the spring 67.

We claim as our invention:

In a machine for driving hoops on barrels or the like, the combination of a reciprocating driving head, means for actuating said driving head and means for guiding the same in its movements, hoop driving devices on

said head having hoop engaging portions arranged at a fixed distance from said head, a stave leveling and centering device adjacent said driving head, means for resiliently connecting said leveling and centering device on said head so as to permit said leveling and centering device to yield relatively to said driving head when said hoop driving devices engage a hoop and said leveling and centering device is engaged by the ends of the staves of a barrel, barrel guiding members on said hoop driving devices adapted to

guide the barrel into position on said leveling and centering device, and one or more of said hoop driving devices being provided with elongated fingers adapted to engage and intercept an edge of the barrel when it is in an inclined position during the placing of said barrel into said machine, whereby said edge is accurately directed towards said guiding members and into position on said leveling and centering device.

WILLIAM W. TREVOR.
DELBERT A. BEREAN.
